COLUMN

George G. Adler, Miami, Fla.

Application December 17, 1937, Serial No. 180,461

1 Claim. (Cl. 72—75)

This invention aims to provide a novel construction of column, adapted to be used either in connection with walls, or independently of the walls, a simple but useful combination of 5 U-shaped and L-shaped blocks being provided, the construction being such that openings are formed in the column through which the concrete filling of the column may pass, to join it- 10 self with the walls. The invention aims, further, to provide a column which may be built up of concrete, without using forms.

It is within the province of the disclosure to improve generally and to enhance the utility of devices of that type to which the present invention appertains.

With the above and other objects in view, which will appear as the description proceeds, the invention resides in the combination and arrangement of parts and in the details of construction 20 herinafter described and claimed, it being understood that changes in the precise embodiment of the invention herein disclosed, may be made within the scope of what is claimed, without departing from the spirit of the invention.

25 In the accompanying drawing:

Fig. 1 shows in perspective, a column constructed in accordance with the invention, assembled with rectangularly disposed walls;

Fig. 2 is a cross section on the line 2—2 of 30 Fig. 1;

Fig. 3 is a cross section on the line 3—3 of Fig. 1;

Fig. 4 is a perspective view showing one of the blocks;

Fig. 5 is a perspective view showing another of the blocks;

Fig. 6 is a perspective view showing a modified form of column, wherein the U-shaped blocks alone are used.

40 In carrying out the invention as shown in Figs. 1 to 5, there is provided a column 1 made up of courses. Each course comprises a U-shaped block 2, including a body 3 and side flanges 4; and L-shaped blocks 5 each comprising a body 6 and a side flange 7. As shown in Figs. 2 and 3 one side flange 4 of the U-shaped block 2 is disposed opposite to the side flange 7 of the L-shaped block 5, and the other side flange 4 of the U-shaped block 2 projecting toward the body 6 of the L-shaped block 5, to form an opening 8.

The construction above referred to is carried out throughout the height of the block, adjoining courses being turned through an arc of 90 degrees with respect to the axis of the column, the openings 8 on one side of the column being disposed at right angles to the openings 8 on another side of the column, so that the concrete filling 10 of the column may pass through the openings 8 and be received as shown at 20 in the openings 14 of hollow walls 11 and 12, arranged 10 at right angles to each other and cooperating with the column 1, as shown in Figs. 1, 2 and 3. A reenforcement 9 may be located in the concrete filling 10.

It will be seen that the invention comprises 15 a novel means whereby a column may be built up of the blocks shown in Figs. 4 and 5, each course having the opening 8, whereby the concrete may interlock, as at 20, with the walls 11 and 12, and bind the walls to the column. 20

The column and the walls may be laid up without the use of forms, and forms are not needed in the pouring of the concrete.

In Fig. 6, parts hereinbefore described have 25 been designated by numerals already used with the suffix "a". In this form of the invention, the U-shaped blocks 2a alone are used, adjoining courses being turned through an arc of 90 degrees, so that the lines 25 of abutment between the arms 4a of the blocks are not in the same 30 vertical line. Its construction is useful when the column is located otherwise than in connection with the walls 11 and 12. The concrete filling shown at 9 of course is used in the form shown in Fig. 6. 35

Having thus described the invention, what is claimed is:

A column comprising superposed courses each made up of a U-shaped block and an L-shaped block, the U-shaped block comprising a body and 40 side flanges, the L-shaped block comprising a body and a side flange, one side flange of the U-shaped block being disposed opposite to the side flange of the L-shaped block, and the other side flange of the U-shaped block projecting toward 45 the body of the L-shaped block, to form an opening through which concrete can flow, and a concrete filling in the column.

GEORGE G. ADLER. 50
